GALVANOMETER HOUSING

Francis E. Lehner, Duarte, Calif., assignor to United
Electrodynamics, Inc., a corporation of California

Filed Aug. 16, 1960, Ser. No. 61,781

Term of patent 14 years

(Cl. D26—5)

FIGURE 1 is a front perspective view of a galvanometer housing embodying my new design;

FIG. 2 is a side elevational view thereof;

FIG. 3 is a top plan view thereof;

FIG. 4 is a bottom plan view thereof; and

FIG. 5 is a rear elevational view thereof.

I claim:

The ornamental design for a galvanometer housing, as shown.
